UNITED STATES PATENT OFFICE.

CHARLES R. PARKER, OF PHILADELPHIA, PENNSYLVANIA, ASSIGNOR TO WIRT & KNOX MFG. CO., OF PHILADELPHIA, PENNSYLVANIA.

HOSE REEL.

Application filed August 23, 1926. Serial No. 130,857.

My invention relates to hose reels and more particularly to reels for garden hose.

The principal object of my invention is to produce a reel which may be shipped in a knocked-down condition and quickly re-assembled without the aid of tools.

Another object of my invention is to so design the parts that the entire hose reel may be shipped in a flat package if so desired.

A still further object of my invention is to produce a light, strong and attractive hose reel that may be sold at a low price.

These objects, and other advantageous ends which will be described hereinafter, I attain in the following manner, reference being had to the accompanying drawings in which—

Figure 1 is a perspective view of the hose reel in its entirety,

Figure 2 a perspective view of the drum frame,

Figure 3 a similar view showing the frame ready for shipment,

Figure 4 a perspective view of the reel frame, and

Figure 5 a perspective view of the assembled drum.

Figures 2, 3 and 5 are drawn to a larger scale than Figure 1, and Figure 4 is drawn to a smaller scale.

The frame comprises a U-shaped main frame 6 and an auxiliary frame or standard 7. The auxiliary frame is secured to the main frame by means of braces 8 having one end secured to each frame by a single rivet. These rivets are driven snugly but not tight so that the brace frame may be swung on the rivets if so desired. Holes 9 are provided in the ends of both the main and auxiliary frames wherein the axle 10 is mounted. Wheels 11 are rotatably mounted on the axle, outside the frame, and are secured to the axle by cotters or other suitable means.

The drum consists of two rings 12 having slots 13 spaced therein. The rings are secured to one another by means of straps 14 having each end secured to a ring by means of a rivet 15 and the straps spaced diametrically opposite each other. The outer part of the drum is composed of two metal sheets 16, having slots near their corners which correspond to the slots 13 in the rings 12. The drum is held together by means of the spokes 17 which pass through the slots in

the metal sheets and rings respectively, as plainly illustrated in Figure 5. Each spoke is provided with a hole 18 in its center wherein the drum axle 19 may be inserted.

While the component parts of the drum frame and of the main frame have been described as being riveted together, it will be readily understood that bolts, screws or other suitable means may be employed.

Assuming that the hose reel has been shipped flat and that the drum is in the condition as illustrated in Figure 3, the rings are swung on the rivets 15 until their planes are parallel to one another. A spoke 17 is slipped through opposite holes in each ring, the two spokes being parallel to one another. The sheets 16 are then slipped over the ends of the spokes and the other two spokes are inserted through the other slots and the spokes so adjusted that the holes 18 coincide. The frame 6 is provided with holes 20 through which the axle may be inserted. The axle is inserted through a hole 20 in one side of the frame 6 and a spacer 21 slipped on to the axle. The axle is then pushed through both sets of spokes, a second spacer slipped on the axle, which is then passed through the hole 20 in the other side of the frame. A spacer 21 is provided between each end of the drum and the frame in order to assure that the drum will rotate freely in the frame.

The frame 6 may be shipped flat by swinging the auxiliary frame on the rivets, which secure the braces to the two frames, so that it lies parallel with the main frame. Instead of riveting, one or both ends of the straps 8 may be bolted and the frames disengaged for shipping. After the frame has been shipped in this condition, the hose reel is set up in the following manner. The U-shaped part of each frame is grasped in either hand and pulled apart until the holes 9 coincide, the axle 10 is then inserted through these holes and the wheels mounted on the axle. Inserting the axle through the holes 9 produces a very rigid main frame.

In carrying out my invention it is important that the slots 13 in the rings 12 and the corresponding slots in the sheets 16 be punched with precision so that the edges of the spokes bear on the outer edges of the slots in the sheets, and thus hold the drum rigid and true to form.

While I have described my invention as

taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

- 10 1. A hose reel including a drum frame comprising a plurality of rings, and means joining the rings together whereby the rings and joining means may be swung into the same plane.
- 15 2. A hose reel including a drum frame comprising a pair of rings, and a pair of straps, means joining the straps to the rings whereby the straps and rings may be swung into the same plane.
- 20 3. A hose reel including a drum frame comprising a pair of annular rings having spaced slots in their peripheries, and a pair of straps, having each end secured to a ring by a single rivet, spaced diametrically opposite each other, whereby the rings and the straps may be swung into the same plane.
- 25 4. A hose reel including a drum comprising an axle, a plurality of annular rings having spaced slots in their peripheries; a pair of straps, spaced diametrically opposite each other, joining the rings to one another whereby the straps and the rings may be

swung into the same plane; slotted metallic sheets, and means for securing the metallic sheets to the rings and the rings to the axle.

5. A hose reel including a frame; a drum revolvably mounted in the frame and comprising an axle, spokes mounted on the axle, slotted rings mounted on the spokes, and slotted metallic sheets mounted on the spokes whereby the spokes hold the drum parts in assembly.

6. A hose reel including a frame; a drum revolvably mounted on the frame and comprising an axle, spokes mounted on either end of the axle, a slotted ring mounted on each set of spokes, a metallic sheet engaging one end of each spoke and another metallic sheet engaging the other end of each spoke, whereby the spokes hold the drum parts in assembly.

7. A hose reel including a U-shaped main frame, a U-shaped auxiliary frame, a wheel axle pivotally connecting the ends of the U-shaped members to one another, wheels on the wheel axle, a strap at each side of the reel having an end separably connected to each frame for holding said frames in fixed relation to one another, a drum axle mounted in the main frame, spokes on the drum axle, rings on the spokes, and drum segments removably connected to spokes and abutting the rings.

In testimony whereof I have signed my name to this specification.

CHARLES R. PARKER.
